UNITED STATES PATENT OFFICE.

DAVID FRANK BROWN, OF BOUND BROOK, NEW JERSEY.

AIRSHIP.

1,374,487.

Specification of Letters Patent. Patented Apr. 12, 1921.

Application filed June 22, 1920. Serial No. 390,823.

To all whom it may concern:

Be it known that I, DAVID F. BROWN, a citizen of the United States, residing at Boundbrook, in the county of Somerset and 5 State of New Jersey, have invented a new and useful Airship, of which the following is a specification.

This invention relates to airships, one of its objects being to provide a structure including a central car adapted to be rotated 10 with a plurality of radial lifting and sustaining planes.

A further object is to provide an airship having separate motors mounted on the respective sustaining planes, it being possible to rotate said motors about their individual axes and relative to the planes on which they are mounted so as to control the speed of rotation of the planes about the central 20 car and also control the direction of flight.

Another object is to provide an airship in which the adjustment of the motors relative to the planes on which they are mounted can be effected by an operator located within the 25 central car.

A still further object is to provide an individual car for each motor adapted not only to house the motor but also to hold an attendant.

30 A still further object is to provide the car with a floor section adapted to be rotated in a direction opposite to the direction of rotation of the car and its radial plane so that, if desired, the occupant of the central car can maintain a fixed position relative to the points of the compass.

With the foregoing and other objects in view, which will appear as the description proceeds, the invention resides in the combination and arrangement of parts and in the details of construction hereinafter described and claimed, it being understood that, within the scope of what is claimed, changes in the precise embodiment of the 45 invention shown can be made without departing from the spirit of the invention.

In the accompanying drawings the preferred form of the invention has been shown.

50 In said drawings—

Figure 1 is a perspective view of the airship viewed from beneath.

Fig. 2 is a transverse section through two sustaining planes and showing therebetween one of the motor carrying gondolas. 55

Fig. 3 is a transverse section through the gondola.

Fig. 4 is a longitudinal section through the central car of the airship.

Fig. 5 is a view partly in plan and partly 60 in section of a portion of the airship and showing the relative positions of the wings, the central car, and the connecting platforms, the reinforcing braces and other structural details being removed. 65

Fig. 6 is a bottom plan view of the pedestal of the machine.

Fig. 7 is a section therethrough.

Referring to the figures by characters of reference 1 designates a triangular central 70 structure which can be suitably reinforced and is rigid throughout, this structure being built around a central car 2 adapted to contain the operator and the various controlling instruments and mechanism used by 75 him. Extending radially from the angle portions of the triangular structure 1 are superposed sustaining planes 3 held properly spaced by struts 4, these planes being preferably in line with the upper and lower 80 members 5 of the triangular structure and which members are also held properly spaced by struts such as shown at 6. As shown the planes 3 can be provided with suitably arranged stay wires 7 or the like, 85 the upper wires extending to a circular connecting ring 8 supported above the triangular structure 1 by standards 9 and the said upper stay wires radiating from this ring to the upper sustaining plane as shown. 90

Arranged under the triangular structure is a pedestal consisting of connected upper and lower rings 10 concentric with the vertical center of the airship and said lower rings being mounted on antifriction bearings 11 carried by a base 12. A king bolt 13 connects the centers of the ring 10 and the base 12. Thus it will be seen that when the base is on the ground the entire airship 95 can rotate thereon about the king bolt 13 at the center thereby making it possible to obtain a velocity sufficient to cause the planes 3 to lift the entire machine from the ground. This base 12 is also advantageous 100

because when the machine is rotating, as hereinafter explained, to allow it to be lowered while under control of the driver, the base will first contact with the ground and 5 will remain stationary while the balance of the machine continues to rotate under the momentum imparted thereto.

Supported between the upper and lower sustaining planes of each pair is a gondola 14 having spindles 15 and 16 extending downwardly and upwardly respectively therefrom and journaled in longitudinal strips 17 which are arranged between the planes 3, said planes being mounted to swing 10 relative to the strips 17 because of hinge connections such as shown at 18. Each gondola is provided with a motor 19 for driving a propeller 20 located at the front end of the gondola and sufficient room is provided 15 in the gondola to accommodate one or more attendants whose business it is to look after the engine and adjacent portions of the airship. The lower spindle of each gondola is provided with an antifriction bearing 21 20 and also with a sheave 22. Mounted on this sheave is an endless belt 23 extending to one of a series of sheaves 24 mounted on a vertical shaft 25 journaled in the car 2. Worm 25 gearing indicated generally at 26 is provided for rotating the shaft 25 and can be operated by a hand wheel 27. One sheave or pulley 24 is provided for each gondola and it will be obvious that by rotating the hand wheel 27 all of the gondolas will be 30 rotated simultaneously relative to the planes 3 between which they are mounted. Under normal conditions the gondolas are arranged so as to follow each other in a circle, the propellers exerting a pull at tangents to said 35 circle. By means of the hand wheel 27, however, the said gondolas can be shifted so as to pull along parallel lines, thus causing the machine to move forwardly without rotating. By gradually shifting the gondolas out of parallel their directions of pull 40 will be such as to cause the machine to rotate bodily with the center of the car 2 as an axis and the speed of rotation will increase until the gondolas are all shifted to the position 45 first mentioned wherein they all pull along lines tangent to the same circle.

In addition to the means employed for shifting the gondolas, an additional shaft 28 may be mounted in the car 2 and operated 50 through worm gearing 29 from a hand wheel 30. This mechanism may be used for driving belts 31 whereby the sustaining planes can be tilted about longitudinal axes for the purpose of changing the angle of incidence, thereby to control the flight of the machine. The specific means for imparting 55 rocking movement to the planes when the belts 31 are actuated is a matter of mechanical detail and need not be described specifically.

The floor of the central car 2 is provided with a central opening 32 in which is located a circular floor section 33 secured to a shaft 34 journaled in the car 2. Arranged under the floor section 33 and secured to the shaft 70 34 is a grooved wheel 35 supported by antifriction bearings 36. This wheel 35 is adapted to be driven by a belt 37 or the like receiving motion from a motor 38. This motor is provided with suitable brake 75 mechanism under the control of a pulley 39 adapted to be operated by a belt 40 extending from a pulley 41 secured to a shaft 42 which is journaled in the lower portion of the shaft 34 and is adapted to be operated 80 by suitable mechanism under the control of a hand wheel 43. Thus the operator by actuating the wheel 43 can transmit motion to the pulley 39 and thereby control the speed of the motor by the use of any well known brake mechanism provided for that purpose.

Tail planes 44 can be connected to the back end of one pair of sustaining planes 3 and are adapted to be operated by the occupant of the car 2, thus to control the direction of flight.

As heretofore pointed out the machine, when at rest, stands upon the pedestal 10 bearing on the base 12 contacting with the ground. The gondolas 14 are shifted to positions at right angles to the longitudinal axes of the planes 3 and the motors are set in motion. The propellers will thus act to rotate the entire machine about its vertical 100 center until the velocity obtained becomes sufficient to lift the machine bodily from the ground. As soon as this velocity has been obtained the operator tilts the planes 3 which will immediately displace air downwardly and the entire machine will thus operate as a helicopter and cause the machine to travel vertically. The machine will rise to the desired altitude and during the rotation of the machine the motor 38 will drive 110 the floor section 33 in a direction opposite to the direction of rotation of the planes 3 so that the occupant of the floor section 33 can maintain a fixed position relative to the points of the compass, if so desired. By 115 manipulating the hand wheels 27 and 30 the positions of the gondolas can be changed at will and the tiltable planes 3 can be adjusted. Thus when the machine reaches its proper altitude the rotation of the planes 120 can be stopped, said planes can be tilted to desired angles, and all of the propellers can be caused to pull the machine forwardly so that said machine will operate as an ordinary aeroplane. While the machine is traveling in this manner its flight can be controlled by manipulating the tail planes 44.

It will be noted that by providing a machine such as described it will be possible to hover over a fixed point, to ascend or de- 130

scend vertically, and to glide forwardly from a fixed point after the manner of an aeroplane.

In the illustrations forming a part of this application no attempt has been made to show some of the various mechanical details as the drawings are more in the nature of diagrams for illustrating the features of construction and operation, constituting the 10 present invention.

What is claimed is:

1. In an airship a plurality of radially extending planes, a motor propelled propeller movable with each of the planes, said 15 propellers being driven simultaneously to swing the planes about a common center, and means for shifting the propellers relative to the planes to vary the speed of rotation of the planes about said center and to 20 propel the machine forward bodily.

2. In an airship the combination with radially extending planes, of motor driven propellers carried by the planes, means under the control of an operator for simultaneously shifting the propellers relative to the planes thereby to move the planes in a 25 circle about a common center or to move the machine bodily in a forward direction.

3. In an airship the combination with 30 radially extending sustaining planes disposed in pairs, of a motor supported between the planes of each pair, a propeller driven by each motor, means under the con-

trol of one operator for simultaneously adjusting all of the motors angularly relative 35 to the planes, said propellers operating to drive the planes about a common center or to propel the machine bodily in a forward direction.

4. An airship including radially extending 40 pairs of superposed planes mounted for tilting, a motor interposed between the planes of each pair, a propeller driven by each motor, means under the control of a single operator for simultaneously shifting 45 all of the motors to vary the direction of pull of the propellers relative to the planes, thereby to drive the planes about a central axis or to move the machine bodily in a 50 forward direction.

5. In an airship the combination with a central structure and wings extending radially therefrom, of motor driven propellers mounted on the wings for driving the wings about a common center, a floor section carried by the central structure, and means for rotating said floor section in a direction opposite to the direction of rotation of the central structure.

In testimony that I claim the foregoing 60 as my own, I have hereto affixed my signature in the presence of two witnesses.

DAVID FRANK BROWN.
